STAIRWAY

Louis Blum and William J. Horgan, Jr., Pittsburgh, Pa., assignors to Blumcraft of Pittsburgh, Pittsburgh, Pa., a firm consisting of Hyman Blum, Louis Blum, Max
Blum, and Harry P. Blum

Filed Dec. 13, 1963, Ser. No. 77,791

Term of patent 14 years

(Cl. D13—7)

FIG. 1.

FIG. 2.

FIG. 3.

FIG. 4.

FIG. 1 is a side elevational view of a stairway embodying our new design;

FIG. 2 is a plan view of a stairway embodying our new design;

FIG. 3 is a perspective view of a stairway embodying our new design; and

FIG. 4 is a sectional view taken on line IV—IV of FIG. 3.

The dominant feature of our new design is the suspension of the stairway treads from above without direct connection between the treads.

We claim:

The ornamental design for a stairway, as shown and described.
